(57) **CLAIM**

The ornamental design for a planetarium projector, as shown and described.

DESCRIPTION

FIG. 1 is a front elevational view of a planetarium projector showing my new design.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is a front, left side and top perspective view thereof.

FIG. 8 is a rear, right side and top perspective view thereof.

FIG. 9 is a cross section taken along line 9-9 shown in FIG. 1; and,

FIG. 10 is a cross section taken along line 10-10 shown in FIG. 3.

The broken lines shown in the figures form no part of the claimed design.
